UNITED STATES PATENT OFFICE.

BENJAMIN LAWRENCE, OF NEW YORK, N. Y.

DESIGN FOR WRITING-PAPER AND ENVELOPES.

Specification forming part of Design No. **7,962**, dated December 29, 1874; application filed December 17, 1874.
[Term of Patent 14 years.]

To all whom it may concern:

Be it known that I, BENJAMIN LAWRENCE, of the city, county, and State of New York, have invented a new and original Design for Writing-Paper and Envelopes, of which the following is a specification:

My design for writing-paper, &c., is fully represented in the accompanying drawing, to which reference is made, the same being a dark ground, *a*, with lines *b* of lighter color than the ground color.

The design applies to all ruled or lined paper for writing.

I claim as my invention—

The design for writing-paper and envelopes, consisting of a dark ground and light lines, substantially as specified.

BENJM. LAWRENCE.
